COMBINED LETTER OPENER AND SCISSORS OR SIMILAR DESK TOOL

Clayton A. Laughlin, Minneapolis, Minn., assignor to
Arthur Salm Inc., Chicago, Ill., a corporation of
Illinois

Filed May 20, 1968, Ser. No. 12,017

Term of patent 14 years

Int. Cl. D8—02

U.S. Cl. D8—104

FIG. 1 is a plan view of a combined letter opener and scissors incorporating my new design;

FIG. 2 is a left side view of the combined letter opener and scissors of FIG. 1;

FIG. 3 is a top end view of the combined letter opener and scissors of FIG. 1;

FIG. 4 is a bottom end view of the combined letter opener and scissors of FIG. 1;

FIG. 5 is a plan view of the rear face of the combined letter opener and scissors of FIG. 1;

FIG. 6 is a plan view of one face of the combined letter opener and scissors of FIG. 1 showing the scissors in the open position;

FIG. 7 is a plan view of the rear face of the combined letter opener and scissors of FIG. 1 showing the letter opener in the open position.

The essential features of the instant design reside in the handle portion thereof.

I claim:

The ornamental design for a combined letter opener and scissors or similar desk tool, substantially as shown and described.
